UNITED STATES PATENT OFFICE.

SAMUEL S. ROSE, OF AMADOR CITY, CALIFORNIA, ASSIGNOR TO ROSE MANUFACTURING COMPANY, OF SAN JOSE, CALIFORNIA, A CORPORATION OF ARIZONA TERRITORY.

TRACTION-ENGINE.

No. 884,685.

Specification of Letters Patent.

Patented April 14, 1908.

Application filed August 24, 1905. Serial No. 275,686.

To all whom it may concern:

Be it known that I, SAMUEL S. ROSE, citizen of the United States, residing at Amador City, in the county of Amador and State of California, have invented certain new and useful Improvements in Traction-Engines, of which the following is a specification.

My invention relates to improvements in traction engines.

10 The object of my invention is to provide a traction engine for use in orchards which may be operated in all positions or under any conditions encountered therein and whose operation can be accomplished with but little instruction and effort by one not skilled in the art.

My invention consists in the novel combination and arrangement of parts shown in the accompanying drawing, described in the 20 following specification and claimed in the appended claims.

Referring to the accompanying drawing: Figure 1 is a side elevation of said machine, except the complete view of the bevel- 25 geared idlers and clutch mechanism shown in Fig. 4. Fig. 2 is a plan view of said machine, excepting said view as shown in Fig. 4. Fig. 3 is a detail of the ball bearing ring. Fig. 4 is a detailed view of the bevel geared idlers 30 and the clutch mechanism intervening and parts for the operation of the same. Fig. 5 is a side view of one of said idlers and the bevel for operating the same when said bevel is in contact with an idler engageable 35 with the said clutch mechanism. Fig. 6 is an enlarged detail of said idlers and clutch mechanism and the bevel for operating either of said idlers when in contact with the clutch mechanism.

40 In the figures 1 shows a suitable frame for the engine.

2 represents journals in which are mounted axles 3, having thereon side wheels 4 and also driving sprockets 5 and which are driven 45 by means of the chains 6 and the sprockets 7 on the shaft 8, said sprockets 7 being so driven by the clutches 9, and the bevel gear 10 in mesh with the bevel 11, mounted on the shaft 12, which is driven by suitable motive power. Bevels 15' are mounted on shaft 8 and bevel 14' engages said bevels, being controlled by clutch 23'. The bevel 14' is mounted on one end of shaft 14 and said shaft 14 consists of two parts connected by joint 15 as shown in Figs. 1 and 5, and said

shaft 14 supports and turns gear 16 which engages gear 16' on shaft 18. On shaft 18 is mounted a block 19 containing a hauling link 20. The clutch 23' is slideable on shaft 8 and the bevels 15' idle on said shaft, said 60 clutches keyed to shaft 8 as shown in Fig. 6. The front or steering wheel 21 is mounted on a circular band 22, having ball bearings 23 on which rests the annular flange 24. A sprocket chain 25 engages corresponding 65 teeth on a drum 26, and is turned by the sprocket wheel 27 which is caused to revolve by the worm wheel 28 and worm 36, rods 29, joint 29' and a hand wheel 30.

31 designates a gasoline engine which fur- 70 nishes the motive power.

32 and 33 show pivoted rods for the engagement and disengagement of the clutches.

34 represents a rod having the part shown above the clutch 23' of circular shape, and 75 surrounding a circular ridge in said clutch, the lateral movement of said rod causing the engagement and disengagement of said clutch and either bevel 15' as may be desired, the engagement of said clutch and a 80 bevel 15' causing through the intervening mechanism the turning of the worm 18, whereby the block 19 and ring 20 are caused to move by the turning of the worm in appropriate depressions in said block, the move- 85 ment of one of said bevels 15' causing the movement of said block and ring in one direction and the movement of the opposite bevel 15' causing such movement in the opposite direction. The ring 20 is for the securing of 90 a vehicle or other object to be drawn and it may be shifted to such position on the worm as to provide for a wide path for its progress in turning corners or moving angularly. Levers or other appropriate means for the 95 movement of the pivoted rods 32 and 33 are shown at points 35. By the movements of the levers or means mentioned the shifting mechanism having connection therewith as shown and described, may be operated so 100 that in a turning movement the outer wheel 4 may be caused to revolve while the inner wheel 4 is disengaged from the propelling mechanism, such outer wheel and the appropriate turning of wheel 21 causing such 105 change in the direction of the progress of the machine. The shaft 8 runs in bearings 37 which may be bolted or otherwise secured to frame 1. The bevels 15' may be prevented 110 from moving laterally further than desired

by pins 40 inserted in shaft 8 or by other appropriate means. When it is desired that one of the bevels 15' shall engage bevel 14' the clutch 23' is moved so that the teeth of 5 said clutch shall intermesh with the teeth opposite thereto secured to the said bevel 15', whereby said shaft is caused to rotate in the desired direction. Should the other direction of rotation of the shaft be desired the 10 clutch is moved laterally in the contrary direction whereby the opposite teeth of the clutch are caused to engage the teeth secured to the opposite bevel 15' causing such rotation, the disengaged bevel thereby idling on 15 the shaft. Through the appropriate movement of said clutch the worm or shaft 18 may be caused to rotate in either direction so as to bring block 19 and ring 20 to any desired position on said worm.

20 By reference to said drawings and the foregoing specification any one skilled in the art may make said machine.

For the operation of said machine I prefer the clutch mechanism shown in Figs. 4 and 25 5 and hereinbefore described.

Having thus described my invention what I claim as new and desire to secure by Letters Patent is:—

1. In a traction engine the combination of 30 a supporting frame, side carrying wheels and driving sprocket-wheels mounted on journaled axles; chains and sprocket-wheels mounted on the central transverse shaft for the revolution of said driving sprocket-wheels; a bevel wheel centrally positioned on 35 said shaft engaging a counter-bevel wheel mounted at one end of a central longitudinal shaft, clutches upon said transverse shaft for connecting and disconnecting the 40 sprocket-wheels with the power mechanism, rods and levers for the movement of said clutches, a front steering wheel mounted in a circular band, ball bearings in said band, an annular flange on said band a drum 45 said band, a sprocket chain engaging the teeth of said drum, a sprocket-wheel for turning said drum, rods connected by a joint, and a worm gear for turning said sprocket wheel, bevel wheels loosely mounted 50 ed at one end of said central transverse shaft, a clutch slidably on said last named shaft between said bevel wheels and having teeth arranged for engagement with teeth upon said wheels, a shaft having a counter-bevel wheel for alternately engaging said 55 last-named bevel wheels and having a joint connected to a rod running longitudinally, a gear secured to said rod, a transverse worm having a gear engaging the gear so

secured and a block and link movable by 60 said worm, substantially as described.

2. In a traction engine in combination with a gasolene power generator, a supporting frame sustaining side carrying wheels, driving sprocket-wheels, means for the revolution of said driving sprocket wheels; a bevel wheel centrally positioned on a shaft 65 engaging a counter-bevel wheel mounted at one end of a central longitudinal shaft, clutches upon said transverse shaft for connecting and disconnecting the sprocket-wheels with the power mechanism rods, and levers for the movement of said clutches, a circular flanged band containing ball bearings, a drum with annular teeth in said band, 70 a sprocket wheel for turning the said drum, means engaging the teeth of said drum and said sprocket wheel, rods connected by a joint, and worm gear for turning said sprocket-wheel, substantially as described. 80

3. In a traction engine, a mechanism for changing the place of attachment of the vehicle or object to be drawn, comprising bevel wheels loosely mounted on one end of a central transverse shaft, a clutch slidably 85 mounted between said bevels arranged to mesh with said wheels, a shaft supporting a bevel positioned to engage either of said bevel wheels, a longitudinal shaft joined to the shaft so mounted; a gear secured to said longitudinal shaft, a transverse worm supporting a gear engaging the gear so secured, and a block and link movable by said worm substantially as described.

4. In a traction engine a mechanism for 95 changing the place of attachment of the vehicle or object to be drawn, comprising bevel wheels loosely mounted on one end of a central transverse shaft, means for preventing the outward lateral movement of 100 said wheels, a clutch slidably mounted between said bevel wheels arranged to mesh with said wheels, means for shifting said clutch, a shaft supporting a bevel positioned to engage either of said bevel wheels, a longitudinal shaft joined to the shaft so mounted; a gear secured to said longitudinal shaft, a transverse worm supporting a gear engaging the gear so secured, and a block and link 105 movable by said worm substantially as described. 110

In testimony whereof I affix my signature in presence of two witnesses.

SAMUEL S. ROSE.
